UNITED STATES PATENT OFFICE.

CHARLES WALTER KLEMENT, OF TORONTO, ONTARIO, CANADA.

STREET-STOP SIGNAL FOR VEHICLES.

Application filed October 31, 1927. Serial No. 230,003.

This invention relates to a street stop indicator for vehicles, as described in the present specification and illustrated in the accompanying drawings which form part of 5 same.

The invention consists essentially of the novel features pointed out broadly and specifically in the claims for novelty following a description containing an explanation in 10 detail of an acceptable form of the invention.

The objects of the invention are to provide an efficient indicator requiring very little of the operator's time to operate and regulate; to simplify the construction and installation 15 of such indicators, whether electrically or manually operated; to so design the indicator that it can be made into a single detachable unit; to have means whereby the sequence of stops on one route is changed 20 automatically with the direction of travel; to so design such a device that it can be made into a practical size while at the same time provide for a great number of routes and a large number of street stops to each 25 route.

In the drawings, Figure 1 is a view of the device in elevation with the casing in section.

Figure 2 is a view in section of the canvas-operated switch mechanism.

Figures 3 and 4 are two views of the switch mechanism used for automatically skipping stops.

Figure 5 is a fragmentary front view of one of the stencilled belts and the blank or unstencilled belt.

Figure 6 is a side view of Figure 5.

Figure 7 is a front elevation view of the motor and clutch mechanism.

Figure 8 is a diagram illustrating the 40 circuits or wiring used in the device complete.

Figure 9 is a view in elevation of the foot and manually operated mechanism for actuating the device.

Figure 10 is a perspective view of one part 45 of the foot-operated mechanism.

Figure 11 is a bottom plan view of Figure 12.

Figure 12 is a section on line 12-12 in 50 Figure 9.

Like numerals of reference indicate corresponding parts in the various figures.

Referring to the drawings, 10 designates the roof of a vehicle such as a street car, through which roof an opening 11 is made.

12, 13 and 14 are rollers or reels loosely mounted on the upper members 15 of the

rigid frame 16. The reels 12 and 13 have each a belt or canvas 17 and 17^A, respectively, mounted or wound therearound and stencilled consecutively with the names of the 60 street stops on each route or circuit. One, two or more of such reels can be used so as to equip each street car with enough canvas to include all the different routes comprised in the entire railway system. Take for instance, "route A": all stops on that route are arranged consecutively on the belt 17, "First Avenue, Second Avenue", etc.; on the same canvas immediately after "route A" is stencilled "route B", consisting of the stops 70 "First Avenue, Second Avenue", etc.; and so on until the entire canvas 17 on the reel 12 is filled. The canvas 17^A on reel 13 is similarly printed or stencilled. The reel 14 has a short belt 18 left blank or unstencilled, this 75 belt being used to operatively connect with either of the belts 17 or 17^A and wind same around the reel 14, which becomes the driving reel when the belts travel in the direction of the arrows (see Figure 1). The loose end of the belt 18 is further provided with suitable means for fastening with corresponding means in the loose end of the belts 17 and 17^A, as with soft metal hooks 20 secured to the belt 18 near the loose end thereof and engaging 80 in holes or slots 21 in each of said belts 17 and 17^A. Once any of the belts 17 and 17^A can be operatively connected with the belt 18, any of the reels 12 and 13 can be driven or made to drive to wind or unwind the 85 canvas.

Hooks 21^A are provided as shown, whereby the loose end of each canvas or belt can be releasably fastened thereto and kept out of the way (as best illustrated in Figure 1). 90 An idler or loose pulley 22 is positioned to be within the vehicle when the device complete is assembled or placed in operative position upon the vehicle, this idler being engaged by the belt so as to cause same to be brought into the vehicle through the opening 11 and adequately exposed to the view of the passengers. A frame or casing 23 is built around the idler (as shown in Figure 1) and is provided with a hinged glass-paneled door 24. A suitable electric motor 27, preferably a small induction induction motor, is used as the driving power of the device, it being located underneath the reserve reel 13.

In order to facilitate the building and installation of the device, whether into already-constructed cars or in cars in process of man-

ufacture, the reels, motor and idler are mounted on the frame 16, or in other words, the device complete forms a unit that can be placed into and removed from a vehicle. Accordingly, the frame is formed substantially as shown, consisting of two parallelly-arranged units or frame members each having the upper and lower horizontal parallel members 15 and 15^A and the upright end members 15^B, the two frame units being retained in their spaced relation by means of spacers 15^C; the lower members 15^A are bent downwardly as at 15^D to provide a centrally located lower portion 15^E upon which the motor is supported and from which the idler is rotatably or loosely suspended by means of the bracket 28. A cover or lid 29 is removably secured upon the roof over the opening 11 so as to close said opening. Ready access is gained into the device mechanism from the roof by removing the lid, and similarly the device can be easily placed into operative position and as easily removed.

The reels are each provided with a sprocket 30 rigid therewith and in alignment each with a corresponding or co-acting sprocket 31 loosely mounted on the motor shaft 32. Sprocket chains 33 are trained between the sprockets 31 and 30 so as to rotate the reels 30 from the motor. In order to separately rotate the shaft sprockets 31, or in other words to separately propulse the chains 33 and therefore rotate their corresponding reels, a suitable clutch mechanism is provided: rigid with each of the shaft sprockets 31 is a gear 34 adjacent which is a collar 35 rigidly secured upon the motor shaft; each collar has a lever, 36 and 36^A, pivotally mounted upon each of said collars as shown; each lever can be turned to engage with or clear the corresponding gear 34; by referring to Figure 7, it will be seen that the levers are here shown in such a position that the only sprocket chain now being propelled is one of the end ones; if this chain therefore drives the reel 14, then this reel becomes the driving reel, while the other two reels are free, the reel 12 being driven and the canvas travelling in the direction of the arrow (Figure 1). In order to retain the levers 36 and 36^A in neutral or inoperative position, or in operative position, a tensioned spring 36^B is provided in the lever 36, and a number of teeth 36^C and a spring-actuated finger 36^D are provided on the lever 36^A, all as best shown in Figure 7.

The canvas is provided with uniformly spaced holes, perforations or slots 40 situated in each of the divisions enclosing the street stops; the switch mechanism 41^A positioned to lie in the path of the canvas 17 or 17^A, as the case may be, is designed to co-act with the said perforations in stopping the motor 27 at regular distance intervals travelled by the canvas. Thus whether the driving reel 65 is partly empty or is full, the distance inter-

vals travelled by the canvas when actuated or propelled by the motor are always constant, with the result that at every stop the proper street name appears in the centre of the glass door 24. The switch mechanism shown herein consists of a casing or box 42 adapted to be secured to a fixed part, having an arm 41 pivoted at 42^A, on the end of which is a roller or cam 44 riding or rolling on the canvas; the arm is normally held in a position substantially at right angles to the canvas by means of a tension spring 45 attached at one end to one end of said arm and at the other end to the casing; the arm carries two contacts 46 and 46^A electrically connected to a lead wire 47 and positioned to engage the spring contacts 48 or 48^A electrically connected to another lead 47^A, when said arm is swung out of the normal position which it is forced to assume under the action of the spring 45. When the canvas is actuated or propelled and the roller on the arm 41 is clear or disengaged from any of the slots 40, or is in other words riding upon the canvas, the arm is swung from its normal position and one of its contacts 46 or 46^A engages one of the corresponding contacts 48 or 48^A, according to the direction of travel of the canvas.

The canvas rides over the rollers 49 positioned near the switch mechanism, and in order to retain the canvas under slight tension the reels are provided with suitable brakes that slightly resist their rotation. The drawings disclose a small corrugated wheel 50 rigid on the shaft of each reel upon which rides a spring 51 having the end curved as at 52; irrespective of the direction of rotation of the reel, the spring slides or slips on the wheel while at the same time braking same.

The motor 27 is included in the main circuit, represented by the lead wires 50 and 50^A, in which is a spring button switch 51 of any suitable type or design; the motor is therefore started or operated by pressing upon the button to electrically connect the motor to the source of electricity. In the main circuit is a suitable two-way switch 50^B whereby the motor can be reversed. The lead wires 47 and 47^A are connected to the lead wire 50^A, as shown in Figure 8, so that these leads 47 and 47^A form a supplementary or second circuit whereby the switch mechanism 41^A can be operated to electrically connect the motor to the source of electricity after the button switch 51 is released. An electric bulb 52^C is preferably provided and located as shown in Figure 8, so as to warn the operator when the switch mechanism 41^A operates to close the circuit; at this signal the operator releases the electric button 51.

It is sometimes found in some street railway systems, routes or circuits in which stops are skipped when travelling in one direction, for instance taking route A going north, the sequence of stops is "First Avenue, Second

Avenue" . . . and "Twentieth Avenue"; going south the stops are "Twentieth Avenue" . . . "Fourth Avenue, Third Avenue", ("Second Avenue" skipped) and "First Avenue". In order to provide for this condition, a third switch mechanism 52 is provided, co-acting with the belt and electrically connecting the motor to the source of electricity when the motor would otherwise be disconnected by the automatic action of the switch mechanism 41^A. This switch 52 is included in a third circuit represented by the lead wires 53 and 53^A connected as shown in Figure 8 to the lead 50^A; the form of switch disclosed herein consists of two spring contacts 54 and 54^A connected to the leads 53 and 53^A, respectively, and formed to normally be out of contact. The belt has the tags 55 on one edge thereof positioned and sized to slidably engage the contact 54^A and press same downwardly to electrically contact with the corresponding contact 54; these tags are secured opposite the stops which are to be skipped, ("Second Avenue" in Figure 5). In order to render this third circuit operative for one direction of travel of the belt—as otherwise this switch would not be necessary—a guide plate 56 curved as at 56^A and 56^B, is positioned and formed to lie in the path of the tags and deflect same or otherwise guide them so as to escape engagement with the spring contact 54^A when travelling in one direction and to cause their engagement when travelling in the opposite direction. For instance, referring to Figures 3 and 4, the tags engage the end 56^A and are guided onto the contact 54^A to close the circuit when the canvas is travelling in the direction of the arrow; "Second Avenue" is now skipped; when the canvas travels in the opposite direction, the tags engage the end 56^B and are deflected to avoid engagement with said contact 54; "Second Avenue" is now a stop. Similarly, if skips are to be made when travelling in both directions, then two such switches as 52 are provided instead of one, and tags provided accordingly. The canvas may be made wide enough to allow room for the transfer points, for instance "B Avenue" and "A Avenue", as suggested in Figure 5.

If desired, the device can also be made to operate with foot and hand by rotating the sprocket 60^A on the end of the motor shaft 32 and providing a suitable governor whereby the distance intervals travelled by the belt are uniform. The sprocket 60^A is detachably secured upon the shaft 32 so as to permit of the complete device being removed from the vehicle. 61 is a sprocket secured to the horizontally-arranged shaft 62, and 63 is a sprocket chain trained between the sprockets 61 and 60^A. The chain is actuated by any one of the two trigger mechanisms 65. The trigger is formed with a flat plate or portion 66

having a round bearing portion 67 adjustably mounted on the rod 68; the portion 66 pivotally carries the finger 71 sized to engage the chain and spring held in operative position by means of a tension spring 73, the anti-clockwise direction of the finger being determined by its engagement with the pin 74; a hollow cylindrical portion 75 having the handle portion 76 is slidably mounted on the end of the bar 68 threaded to receive the nut 75^A; a spring 76^A encircling the rod 68 and positioned between the nut 75^A and the bottom of the portion 75 normally retains the lugs 77 in the notches 78, thus releasably locking the foot operated trigger mechanism in operative or non-operative position, (one shown in position in Figure 9).

The manually operated mechanism is formed with the rods 68 and 68^A vertically journaled in the floor 80 and having the spacer 68^C, the downward motion of which is yieldingly resisted by the action of the spring 79 disposed between the bar 68^C and the bearing 81 and checked or determined by the engagement of the spacer 68^C with the screw 82 of the governor. The bar 68^A is made long enough to extend upwardly to within the easy reach of the motorman. In order to actuate the chain in both directions, the mechanism disclosed in Figure 9 is duplicated on the other side of the vertical centre line C^L bisecting the sprocket 61, only one set of such mechanisms being here shown for the sake of expediency. So as to conveniently locate these mechanisms, it is preferable that the axis of the shaft 62 be laid parallel with the axis of the vehicle and in the motorman's vestibule, so that the required control is well within the easy reach of the motorman or operator. The governor consists of the bevel gear 86 horizontally mounted and meshing with the corresponding bevel gear 84 rigid with the sprocket 61. On the shaft 85 of the bevel gear 86 is a sprocket 89 in alignment with a sprocket 88 loosely mounted on the bracket 89^A. The sprocket 88 is threaded to receive the screw 82 which is enlarged at the bottom end to slide within the hollow base of said bracket; a chain 92 is trained between the sprockets 88 and 89, therefore rotating the screw 82 from the travel of the chain 63. It will be apparent that another set of screws 82, chain 92, sprocket 89, etc., is provided on the opposite side of the shaft 62, as partly suggested by the numerals and dotted lines.

The position of the screw 82 determines the range of action of the trigger or manually operated mechanism by the engagement of the bar 68^C with the top end of said screw. The screw is therefore threaded to such a pitch and so positioned originally in the sprocket 88 that the operative range of the trigger will decrease or increase as the reel is being filled or emptied.

Operation: The roof cover 29 is lifted and the device complete deposited upon the roof and secured in position; the cover is then closed down. The different wire leads are 5 connected in their required positions so as to electrically connect the motor 27 and the various circuits to the source of electricity. The device complete is now ready to be operated.

The direction of rotation of the motor 27 10 is next determined by means of the 2-way switch 50^b. The reel 12 or 13 having the canvas on which is printed or stencilled the route on which the vehicle is now to operate, is next operatively connected to the belt 18 15 on reel 14 and the direction of travel of the belt is determined by turning the corresponding lever mechanism 36 or 36^a, so as to impart rotation to one of the reels from the motor. If the canvas is to travel in the direction of the arrow (Figure 1), the reel 14 is rotated; if the belt is to travel in the opposite direction then reel 12 or 13, as the case may be, is rotated by changing or clutching the proper lever mechanism. To start the 20 motor, the spring button 51 is pressed down to close the main circuit, and is held long enough to allow time for the belt to travel sufficiently to cause the perforation 40 in the belt to clear the roller 44 of the switch arm 41. As soon as the roller is thus clear of the 25 perforation, the button is released and the motor remains electrically connected to the source of electricity, owing to the engagement of the contact on the arm 41 with one of the two contacts 48 or 48^a in the switch mechanism 41^a. When the travel of the belt has brought the succeeding slot or perforation in a position to allow the roller to fall therewith, the connection is broken and the 30 motor stops. After the vehicle has passed that stop, the button is again pressed down, starting the motor and moving the belt; the belt moves until the roller of the switch arm 41 again falls into the next succeeding perforation when the motor is again stopped with the 35 new stop or street name appearing in the window 24, and so on until the end of the route or circuit has been reached. Before the vehicle proceeds on the return trip, the two-way switch is reversed so as to reverse the direction of rotation of the motor.

The same operation as just described is 40 repeated until the vehicle has again reached the starting point. If on the way down stops 45 are to be skipped, as many stops are skipped as there are tags; owing to the engagement of the tags with the switch contact 54^a, which is thus pressed down to engage the corresponding contact 54 and electrically connect the 50 motor to the source of electricity, notwithstanding the breaking of the circuit by the automatic operation of the switch mechanism 41^a.

If the device is operated mechanically, 55 either by the foot trigger or the manually-

operated bars, the finger 71 engages the chain 63, forcing same downwardly and therefore rotating the gear 61 and shaft 32 by varying increments but moving the canvas by uniform distance increments.

What I claim is:

1. In a street stop indicator, a pair of spaced reels having a belt wound therearound and extending therebetween, means including an electric motor for alternately driving one of said reels, a main electric circuit including said motor therein, a switch mechanism in said circuit co-acting with said belt and adapted for breaking said circuit at regular distance intervals travelled by said belt, a second circuit and a button therein for starting said motor when said main circuit is broken by said switch mechanism, and a third circuit and a switch mechanism therein co-acting with said belt and adapted for electrically connecting said motor to the source of electricity when said belt travels in a predetermined direction and when said first-mentioned switch mechanism breaks said first-mentioned circuit. 90

2. The combination with a vehicle having a roof and an opening therethrough, of a frame adapted to be laid upon said roof, an idler suspended from said frame and projecting into said vehicle through said opening when said frame is lying upon said roof, a pair of reels loosely mounted on said frame having a belt wound therearound and extending therebetween and engaging said idler, means for alternately driving one of said reels, and a cover removably secured over said opening. 95

3. The combination with a vehicle having a roof and an opening therethrough, of a frame having lower members adapted to rest upon said roof and a substantially central portion extending below said lower members and formed to project into said vehicle through said opening when said members are resting upon said roof, a pair of reels loosely mounted on said frame having a belt wound therearound and extending therebetween, an idler loosely mounted under said central portion and engaged by said belt, means for alternately driving one of said reels, and a cover removably secured over said opening. 105

4. The combination with a vehicle having a roof and an opening therethrough, of a frame having members adapted to engage said roof and a centrally-located portion thereof formed to project into said vehicle through said opening, a pair of reels loosely mounted on said frame having a canvas wound therearound and extending therebetween, an idler loosely mounted under said centrally-located portion and engaged by said canvas, means including a motor for alternately driving one of said reels, and a cover removably secured over said opening. 120

5. In a street stop indicator, a plurality of 125

loosely mounted reels having each a stencilled belt wound therearound, a loosely mounted reel having a short belt wound therearound for operative connection with the loose end 5 of any of said stencilled belts, and means for alternately driving one of said reels.

6. In a street stop indicator, a plurality of loosely mounted reels having each a stencilled belt wound therearound, a loosely mounted 10 reel having a short belt wound therearound for operative connection with the loose end of any of said stencilled belts, means including an electric motor for alternately driving one of said reels, an idler positioned to be engaged 15 by any of said belts when operatively connected to the belt in said last-mentioned reel, and a switch mechanism positioned in the path of the belts and adapted to stop said motor at regular distance intervals travelled 20 by said belts.

7. In a street stop indicator, loosely mounted reels having sprockets rotating therewith and a stencilled belt wound therearound and extending therebetween, a motor 25 having shaft extensions, sprockets loosely mounted on said shaft extensions in alignment with said sprockets on said reels, chains trained between the co-acting sprockets on said reels and shaft extensions, and separate 30 means for clutching said shaft extension sprockets with said motor shaft.

8. In a street stop indicator, a pair of spaced reels having a belt wound therearound

and extending therebetween, said belt having divisions thereon and perforations therethrough opposite said divisions, means including an electric motor for alternately driving one of said reels, a circuit including said motor therein, means for tensioning said belt, a supplementary circuit, a pivoted arm 40 having a roller positioned to be engaged by said belt and engage in said perforations and springheld in a normal position substantially at right angles to said belt, and contacts included in said supplementary circuit and 45 breaking said circuit by the movement of said arm.

9. In a street stop indicator, a pair of spaced reels having a belt wound therearound and extending therebetween, said belt having 50 divisions and tags rigidly secured to said belt opposite some of said divisions, means including an electric motor for alternately driving one of said reels, a circuit including said motor therein, a switch in said circuit at regular distance intervals travelled by said belt, a switch mechanism positioned in the path of 55 said tags, and a circuit including said last-mentioned switch mechanism therein for electrically-connecting said motor to the source 60 of electricity when said first-mentioned switch mechanism breaks said first-mentioned circuit.

Signed at the city of Toronto, this 27th day of September, 1927.

CHARLES WALTER KLEMENT.
